(57) **CLAIM**

The ornamental design for a precious stone cut, as shown and described in the accompanying figures.

DESCRIPTION

FIG. 1 is a top plan view of the precious stone illustrated in FIG. 1;

FIG. 2 is a bottom view of the precious stone illustrated in FIG. 2; and,

FIG. 3 is a side view of an embodiment of a precious stone illustrating an embodiment of my new design for a precious stone cut.

All portions shown in broken lines are environmental and illustrative only and form no part of the claimed design.
